UNITED STATES PATENT OFFICE.

ALLISTER S. LANGILLE, OF CHICAGO, ILLINOIS.

FIRELESS COOKER.

No. 915,612.

Specification of Letters Patent. Patented March 16, 1909.

Application filed July 20, 1908. Serial No. 444,565.

To all whom it may concern:

Be it known that I, ALLISTER S. LANGILLE, a citizen of the United States, residing at Chicago, in the county of Cook and State of Illinois, have invented certain new and useful Improvements in Fireless Cookers, of which the following, when taken in connection with the drawing accompanying and forming a part hereof, is a full and complete description sufficient to enable those skilled in the art to which it pertains to understand, make, and use the same.

This invention relates to what are known in the art as fireless cookers, and the objects 15 of the invention are to obtain a device which will be effective in operation, sanitary, economical in construction, sightly in appearance, and durable; to obtain a device of the kind named which is reversible, that is, a 20 device provided with a base on which the vessels containing the articles to be cooked may be placed and the remainder of the device placed thereover, and also, a device in which the vessels containing articles to be 25 cooked may be placed and a cover placed thereover.

A further object of the invention is to obtain a device from which no appreciable odor will escape when onions, and other like articles are being cooked therein.

In the drawing referred to Figure 1 illustrates a device embodying the invention, in vertical section, when used in such manner as to have a base on which vessels may be 35 set and a body which may be placed thereover. Fig. 2 illustrates the same construction illustrated in Fig. 1 when used with the body of the device in position to form a receptacle in which vessels may be placed and 40 the remainder of such device being placed thereon to form a cover to the receptacle. Fig. 3 is a horizontal sectional view on line 3—3 of Fig. 1, viewed in the direction indicated by the arrows. And Fig. 4 is a top 45 plan view of a device embodying the invention.

A reference letter applied to designate a given part is used to indicate such part throughout the several figures of the drawing, wherever the same appears.

A is the body part or portion of the device, B is a part of the device arranged to co-act with body part A, and constitutes a base on which the body part A is placed, when the 55 device is used in the manner illustrated in Fig. 1, and a cover to the body part A, when

the device is used in the manner illustrated in Fig. 2. The body part A comprises the cylindrical portion a, closed at end a', suitable packing b' between the walls of the 60 cylindrical and end portions, and the edge a'' at the open end of such cylindrical portion. Edge a'' is provided with the annular groove C.

The part or portion of the device which at 65 times constitutes the base on which vessels are placed and at times the cover to a receptacle in which vessels are placed, is constructed with the annular bead D arranged to fit into and co-act with the annular groove 70 C. In the devices which I have heretofore constructed embodying this invention I have made the annular groove d in the part B, so that when the device is used in the manner illustrated in Figs. 1 and 3, a raised platform 75 (b) will be obtained, and also a channel in which water may be placed before setting the body part A thereto.

The bead D is arranged to contact on the sides thereof with the sides of the groove C, 80 but preferably the top of such bead does not come into contact with the bottom of the groove, so that when the device is used in the manner illustrated in Fig. 2, the water which has been placed in such groove C before the part B is placed on part A, with the bead D in such groove, will not all be forced out from such groove, but some of such water will remain in the groove. Water in 85 annular groove d, or in annular groove C, 90 will prevent odors passing out from the interior of the device, while articles are cooking therein.

E is a mat, preferably made of wire, which is placed on part B when the device is used 95 in the manner illustrated in Figs. 1 and 3. I find in practice that when the mat E is made of coiled wire or of metal provided with many interstices, an appreciable effect is obtained, and that the heat is maintained 100 for a given length of time at a higher temperature than when such mat is not used. I attribute this increased effectiveness to the lessening of the conduction of heat from the cooking vessel through part B by the interposition of said mat, constructed as described, 105 between such vessel and such part B.

F is a belt of flexible material fitting to the cylindrical walls of the device and arranged to be placed over the joint produced 110 by putting the parts A and B, into operative cooking position.

Where the device is made of small size it will be found convenient to use the same in the manner illustrated in Figs. 1 and 3; where made of medium size it will at times be more convenient to use the device in the manner shown in Figs. 1 and 3 and at times in the manner shown in Fig. 2, and when made in large sizes it will be found convenient to use the device in the manner shown in Fig. 2. The strength of the person using the device will often determine the manner of its use.

The operation of this device is substantially the same as that of other fireless cookers, to-wit, the article to be cooked, in a heated condition and in a suitable vessel is placed in the interior of the device, the device is closed, and allowed to remain in such closed condition until the cooking is accomplished.

By constructing the edge a'' of the body part A with an annular groove C, and the part B with the bead D to correspond with such groove C, I find great rigidity is imparted to the parts, and a device of considerable size may be constructed with the certainty that a tight joint will be made at all times in the use of the same, and the same will be durable.

30 The walls of the part A, at the ends thereof which I have termed edge a'' , are joined by a sheet metal ring which is formed or stamped up to obtain the groove C; and the co-acting part, attached to part B and provided with bead D, is obtained in the same way. These parts may be oppositely placed, that is, the part provided with groove C may be attached to part B and the co-acting part which is provided with the bead D may be 40 attached to end a'' .

Having thus described my invention what I claim as new and desire to secure by Letters Patent is:—

1. In a device of the character described, a 45 cylindrical body part closed at one end and open at the other end, such cylindrical part comprising an inner and outer wall, with bad heat conducting material disposed between them, and such walls connected at the open 50 end of the cylindrical body part by a ring which is curved on radial lines to obtain an annular groove on the edge of the open end, in combination with an additional part, such

additional part provided with an annular bead arranged to co-act with the annular 55 groove, and provided with an annular groove, such grooves arranged so that one thereof may contain water when the body part and the additional part are joined; substantially as described.

2. In a device of the character described, a body part closed at one end and open at the other end, such cylindrical part comprising an inner and outer wall, with bad heat conducting material disposed between them, and such walls connected at the open end of the cylindrical body part by a ring which is curved on radial lines to obtain an annular groove on the edge of the open end, in combination with an additional part, such additional part provided with an annular bead arranged to co-act with the annular groove, and provided with a raised bed and with an annular groove adjacent to such bed, such grooves arranged so that one thereof may 75 contain water when the body part and the additional part are joined; substantially as described.

3. In a device of the character described, a body part closed at one end and open at the other end, such cylindrical part comprising an inner and outer wall, with bad heat conducting material disposed between them, and such walls connected at the open end of the cylindrical body part by a ring which is 80 curved on radial lines to obtain an annular groove on the edge of the open end, in combination with an additional part, such additional part provided with an annular bead arranged to co-act with the annular groove, and provided with a raised bed and an annular groove adjacent to the raised bed, such grooves respectively arranged so that one 85 thereof may contain water when the body part and the additional part are joined with 90 the body part underneath, and the other may contain water when the cover is underneath, and a mat provided with interstices arranged to be interposed between such device and a vessel therein; substantially as described.

ALLISTER S. LANGILLE.

In the presence of—

CHARLES TURNER BROWN,
CORA A. ADAMS.
